UNITED STATES PATENT OFFICE.

ISIDOR KITSEE, OF PHILADELPHIA, PENNSYLVANIA.

ELECTRIC RELAY.

No. 856,163.

Specification of Letters Patent.

Patented June 4, 1907.

Application filed June 8, 1905. Serial No. 264,279.

To all whom it may concern:

Be it known that I, ISIDOR KITSEE, of the city and county of Philadelphia and State of Pennsylvania, have invented certain new and useful Improvements in Electric Relays, of which the following is a specification.

My invention relates to an improvement in electric relays. Its object is to provide means whereby impulses received may be relayed in an efficient manner.

To this end my invention consists in the arrangement and features as will herein-after be more fully described, illustrated in the drawing, and more clearly pointed out in the claims following the specification:

Referring to the drawings:—Figure 1 is a perspective view of part of a receiving device, here shown as part of the well known siphon recorder used in cable telegraphy, and a relay embodying my invention. Fig. 2 is a diagrammatic view illustrating this relay in a different form. Fig. 3 is a perspective view of a modification of said relay with electro-magnetic receiver. Fig. 4 is a top plan view of part of the device illustrated in Fig. 3 with a modification. Fig. 5 is a top plan view of part of the movable part of a static device, such as a quadrant adapted to be used in connection with the relay as illustrated in Fig. 3. Fig. 6 is a partial sectional and partial diagrammatic view of a device to clear the relay.

A is the well of a receiving device, well known under the name of siphon recorder and used in submarine telegraphy; A—2 is the liquid contained therein; A—1 is the siphon proper. Usually the liquid A—2 consists of ink adapted to make record on the moving paper but as in accordance with my invention such record is unnecessary and the fluid has to be conducting, this fluid A—2 consists of any of the conducting liquids, such as slightly acidulated water or water made slightly caustic.

B, B, are two conducting points, separated from each other by the space B—1; E is a source of current.

C is an electro-magnetic device.

In Fig. 1, the points B, B, are connected respectively through wires 1 and 2, with the interposition of the electro-magnet C, to the source of current E. In this figure C—1 is the movable lever of the electro-magnet, normally, that is, when the device is not energized, against the stop D, and adapted to be brought in contact when energized with the

stop D—1. The armature is connected to wire 3 and the stop D—1 to wire 4. B—2 is a receptacle adapted to catch the fluid dropping through the space B—1.

The operation of this device as illustrated in Fig. 1 is as follows:—When the siphon A—1 is out of alignment with the space B—1, then this space will remain free and non-conducting for the source of current E, but as soon as the siphon centers with its lower end in alignment with said space, then the fluid issuing from this siphon will bridge the space B—1 and will make the same conducting for the flow of the current from E. This flow of current will energize the electro-magnet and the armature will be brought in contact with D—1, thereby closing the circuit of which the wires 3 and 4 are part. This circuit may contain any of the well known translating devices and source of current necessary for the operation of same. The contacts B, B, with their open space B—1 is in reality the relay proper, and the liquid A—2 is only the means to make this relay operative.

In Fig. 2, the relay consists of the contacts B, B, B, separated by the spaces B—1, B—1. This for the reason that if a polarized relay is used, being normally centered in the middle, it should operate the relay, no matter if actuated to the left or right.

In Fig. 3 a receiving device, such for instance as a polarized relay is shown at A, but the movable part is provided with the shield F impervious to the liquid A—2. Instead of, as in Fig. 1, in which the liquid A—2 is carried in accordance with the movement of part of the receiving device, in Fig. 3 the liquid A—2 issues from a stationary source, through the funnel G. As long as the shield F remains directly above the space B—1, the liquid will run through the groove f to any desired point, but as soon as the shield F comes out of alignment with the space B—1, then the liquid A—2 will flow through this space into the receptacle B—2.

In Fig. 4, the shield F is provided with the orifice f—1, which orifice may be used either to carry a microscopic funnel or to be in itself the means through which the liquid will pass if this hole is in alignment with the space B—1.

In Fig. 5 I have illustrated the shield F in a modified form.

In Fig. 6, the armature C—1 is provided with the perforation H—2 for the purpose of

allowing the liquid to escape into the receptacle B-2; this perforation is preferably provided with the guides H.

In the circuit containing the electro-magnetic device may be placed any of the necessary translating devices, and the place where the same may be inserted is indicated by the dotted lines.

The operation of this device is as follows:

- 10 As long as the space B-1 is free and unobstructed, a direct source of current cannot flow through a circuit connected to the contacts separated by such spaces and electro-magnetic devices therefore inserted in such 15 circuit will remain inoperative as long as these spaces remain unconnected, but when either directly or indirectly, through the operation of the receiving device, a conducting liquid is made to pass through one or the other 20 of the spaces B-1, then the circuit will, for all intents and purposes, be closed and the flow of current from the source E will commence and will continue till the liquid has passed the space B-1.
- 25 Instead of liquid a fluid metal, such as mercury may be used. The selection of the kind of liquid to be used must be left to the person in charge of this device, for in different localities or for different contacts, different 30 liquids may be more adaptable. As contacts, either carbon or platinum are preferred, but any other material suitable for the purpose may be used.

- 35 It is impossible to state how great the distance between the points of contact B, B, should be, or how far apart these contacts shall be kept, as this distance has to vary with the requirements for each case. It suffices to say, that where an easy flowing liquid 40 is used, the contacts may only be separated about 1-32 inch, but as in such cases where the liquid may adhere to the points, thus bridging the space, even when not desired, I have recourse to the arrangement as illustrated in Fig. 6, where the points B, B, are carried by the armature C-1 of the electro-magnet C, adapted to be actuated by the opening or closing of the space between these contact-points. When, in this arrangement, 45 the space between the contacts is bridged by the liquid, the circuit therefore being closed, the armature C-1 will move downward and through this movement the space B-1 will be cleared from any adhering liquid globules.
- 50 It is understood that this relay may be used in any of the electric transmission as long as the receiving device is sensitive enough to vary the flow of the liquid through the space B-1.
- 55 I have shown and illustrated different forms of this relay, but it is obvious that other forms may be adapted, the main and underlying principle being only that conducting points normally apart from each

other shall be made to form a conducting path through the flow of a conducting liquid, and that this flow itself or the direction of this flow should be varied in accordance with the incoming impulses.

I have shown in Fig. 1 the contact-points B, B, as provided with means to adjust the air-space between same, which adjustment may be made to suit requirements.

Having now described my invention, what I claim as new and desire to secure by Letters Patent:

1. In telegraphy, a receiving device, a source of liquid therefor, in combination with a localized circuit comprising two conductors insulated by an air-space, and electro-magnetic device in said circuit; the movable part of the receiving device adapted to allow the liquid to over-bridge said air-space and to deflect said liquid from said air-space in accordance with the characters transmitted. 85

2. Means to relay received telegraphic impulses, said means comprising a source of liquid, a receiving device and a localized circuit containing translating device and an air-space, and means for said receiving device to allow the flow of the liquid through said air-space or deflect the same from said air-space in accordance with the impulses transmitted. 90

3. In combination with a receiving device inserted in the receiving circuit, a siphon and liquid therefor, a localized circuit embracing electro-magnet and air-gap, and means integral with said receiving device to cause the liquid to overbridge said air-gap or cause said liquid to flow out of the region of said air-gap. 95

4. A telegraphic relaying device comprising a localized circuit, two air-spaces for same, said circuit embracing a source of current and electro-magnetic device, in combination with a receiving device inserted in the line of transmission, a source of liquid for said device, and means related to said receiving device to overbridge with said liquid one or the other of said spaces, in accordance 100 with the impulses received. 105

5. In combination with a telegraphic receiving device, a localized relay comprising two conductors separated from each other by an air-space, a source of current and electro-magnet, means integral with said electro-magnetic device to actuate said two conductors, a liquid for the receiving device and means at said receiving device to overbridge with said liquid the air-space between 115 said conductors in accordance with the impulses received.

6. In combination with a receiving device embracing a siphon and liquid therefor, and means at said receiving device to deflect said siphon to the right or left, a localized circuit comprising two air-gaps, one of said air-gaps adapted to be closed through the liquid from 120 125

the siphon when deflected to the right and the other of said air-gaps adapted to be closed through the liquid when deflected to the left.

7. In combination, a line of transmission, a receiving device connected to said line, a local circuit embracing an air-space and containing a translating device, a continuous flowing and conducting fluid adapted to bridge the air-space and means operatively related to the receiving device to vary the flow of the liquid through said air-space in accordance with the impulses received.

8. In combination with a receiving device connected to a line of transmission, a relay embracing two conductors separated by an air-gap and secured to the movable part of

an electro-magnet, a local circuit comprising a source of current, the coil of said electro-magnet and said two conductors, said receiving device adapted to bridge the air-space of said two conductors with a conducting liquid in accordance with the incoming impulses.

In testimony whereof, I hereby sign my name in the presence of two subscribing witnesses, this thirty-first day of May, A. D. 1905.
